UNITED STATES PATENT OFFICE.

LOUIS H. BROWN, OF WORCESTER, MASSACHUSETTS, ASSIGNOR TO
MATTHEW J. WHITTALL, OF WORCESTER, MASSACHUSETTS.

DESIGN FOR CARPET.

SPECIFICATION forming part of Design No. 36,128, dated October 28, 1902.

Application filed August 27, 1902. Serial No. 121,259. Term of patent 3½ years.

To all whom it may concern:

Be it known that I, LOUIS H. BROWN, a citizen of the United States, residing at Worcester, in the county of Worcester and State of Massachusetts, have invented a new, original, and ornamental Design for Carpet, of which the following is a specification.

This invention comprises two parts—namely, the design A for a carpet-body and the design B for a border; and I do hereby declare that the drawing accompanying this specification gives and conveys to any one skilled in the art of carpet weaving and manufacture a clear understanding of same and is sufficient to enable such person to use my invention.

The body A shows two groups of geometric

figures appearing alternately on a plain background marked off by Indian characters.

The border B shows the same geometric groups as in the body, arranged in border form with appropriate outer and inner edges.

What I claim as my invention, and desire to secure by Letters Patent, is—

The ornamental design for carpet substantially as shown and described.

In testimony whereof I have hereunto set my hand in the presence of two subscribing witnesses.

LOUIS H. BROWN.
